ATTORNEY

UNITED STATES PATENT OFFICE.

CLAUDE E. PARKER, OF OILTON, OKLAHOMA.

WATCH-REPAIRING DEVICE.

1,282,279.

Specification of Letters Patent. Patented Oct. 22, 1918.

Application filed June 1, 1917. Serial No. 172,265.

To all whom it may concern:

Be it known that I, CLAUDE E. PARKER, a citizen of the United States, residing at Oilton, in the county of Creek and State of Oklahoma, have invented new and useful Improvements in Watch-Repairing Devices, of which the following is a specification.

This invention relates to devices for holding the main springs of watches and for assisting in transferring a main spring to a watch barrel when repairs are to be made.

One object of the invention is to produce a device of the class described in which a main spring may be conveniently kept in properly coiled condition until wanted for use.

A further object of the invention is to produce a simple and efficient device of the character described which will facilitate the placing of the main spring in the barrel without its being touched by the hands of the operator.

A further object of the invention is to produce a simple and improved container in which a main spring may be placed at the factory, enabling a large quantity of springs to be conveniently handled and utilized.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired.

In the drawing:

Figure 1 is a plan view of the improved container.

Fig. 2 is a sectional view of the same.

Fig. 3 is a plan view of the container with a spring coiled within the same.

Fig. 4 is a plan view of the detachable bottom member of the container.

Fig. 5 is a plan view of a watch barrel adapted to receive the spring from the container.

Fig. 6 is a transverse sectional view of the same.

Fig. 7 is a side elevation partly in section

showing the parts in the act of transferring the spring from the container to the watch barrel.

Fig. 8 is a detail view in perspective of 60 one end portion of the spring.

Fig. 9 is a plan view of the top of the spring barrel.

Corresponding parts in the several figures of the drawing are denoted by like characters of reference.

The improved container of the present invention is composed of a cylindrical wall 15 and a movably supported bottom member 16. The wall member 15 is provided at its lower 70 edge with an interior annular flange 17; the bottom member 16 is provided with a corresponding annular groove 18. The bottom member 16 is of a diameter corresponding with the interior diameter of the wall member 15, enabling said bottom member to be easily inserted or removed. When the bottom member is assembled with the wall member, the lower face of said bottom member will lie in the same plane as the lower 80 edge of the wall member, and the flange 19 produced by the groove 18 will be supported on the flange 17 of the wall member. The bottom member 16 is provided with a notch 85 or recess 20 in the marginal edge thereof.

The spring 21 is provided near the outer end thereof with a plate 22 which may be riveted upon or otherwise connected therewith, said plate being provided with tongues 23 that extend upwardly and downwardly 90 with respect to the spring.

The spring barrel 24 is in the main of ordinary construction, being provided on the inner face of its side wall with a projection which is termed the spring hook 25, the same 95 being adapted for engagement with the eye or opening 26 customarily formed near the outer end of the spring. The bottom of the spring barrel is provided, adjacent to the side wall thereof, with a slot 27 adapted to 100 receive one of the tongues 23. The top of the spring barrel which is designated by 28 is provided in the marginal edge thereof with a notch or recess 29 corresponding to the slot 27 in the bottom of the spring barrel 105 and adapted to receive one of the tongues 23.

In the operation of this invention, the spring 21 is placed in coiled condition in the receptacle formed by the members 15 and 16, one of the lugs 23 being permitted to project 110 through the slot 20 in the marginal edge of the bottom member, 16. When the spring is

to be transferred to a watch barrel, the top of the latter is removed, as well as the old spring. The container in which the new spring is held is now placed in inverted position on the watch barrel it being so proportioned that it will rest on the shoulder 30 of the barrel which normally supports the barrel head 28. It is also obvious that the spring must be turned to such a position that 10 the tongue 23 which is exposed upwardly with respect to the container will be in a position to enter the slot 27 in the bottom of the barrel. By a slight pressure on the bottom member 16 the spring will now be transferred from the container to the watch barrel, the hook 25 engaging the eye or opening 26 in the spring. The barrel is now in condition to receive the spring arbor and the head which are assembled therewith in the 20 customary manner.

The improved spring container may be made of metal or of any suitable material such as hard rubber, indurated fiber or the like, or the cylindrical wall portion may be 25 made of one material and the bottom portion of a different material, if so desired.

By coiling the spring in the improved container at the factory, springs may be conveniently packed and shipped, and the convenience of transferring the spring from the 30 container to the barrel will be readily appreciated, as well as the fact that the spring is not necessarily touched by the hands of the operator, thereby avoiding injury by moisture from the hands, and the like. 35

Having thus described the invention, what is claimed as new is:

A container for watch springs comprising a cylindrical wall member having an interior annular flange at the lower edge thereof 40 and a bottom member removably assembled with said wall member, said bottom member having an annular groove engaging the annular flange of the wall member, said bottom member being provided at its periphery 45 with a notch which leads in from the edge of the bottom member and which is greater in depth than the transverse breadth of the flange.

In testimony whereof I affix my signature. 50

CLAUDE E. PARKER.
